D12-20.

OR D 13,388 EX

No. 13,388

Oct 31, 1882

UNITED STATES PATENT OFFICE.

JOHN L. POPE, OF CLEVELAND, OHIO.

DESIGN FOR A WHIFFLETREE-PLATE.

SPECIFICATION forming part of Design No. 13,388, dated October 31, 1882.

Application filed August 15, 1882. Term of patent 7 years.

To all whom it may concern:

Be it known that I, JOHN L. POPE, of Cleveland, in the county of Cuyahoga and State of Ohio, have invented and produced a new and original Design for Whiffletree-Plates, of which the following is a specification, reference being had to the accompanying engraving, forming part thereof.

My invention relates to a design for whiffletree-plates; and it consists in the shown configuration of the article.

In the accompanying engraving the plate is provided with the usual central bolt-hole, which in the present instance is shown of square shape; but of course the shape of the hole is not of any importance as affecting the novelty or general appearance of my design. On either side of the central hole are arranged in line longitudinally of the plate two holes to receive the usual screws for fastening the plates to the

whiffletrees. Around the bolt-hole is a raised tapering portion, which will be found designated by the letter *a*. The sides or edges of the plate are alike in contour, and are bounded by curves, the curve at *b* meeting the S-shaped curve *c c'* at both the extremities of the former. At *d* the S-shaped curves terminate, and the remaining portion of either end of the plate is semicircular in form.

What I claim as my new design, and desire to secure by Letters Patent, is—

A whiffletree-plate having substantially the configuration shown and described.

In witness whereof I have hereunto set my hand this 22d day of June, 1882.

JOHN L. POPE.

In presence of—

CHAS. W. MOSES,
C. M. COPP.
